UNITED STATES PATENT OFFICE.

PHILIP T. DODGE, OF BROOKLYN, NEW YORK, ASSIGNOR TO MERGEN-
THALER LINOTYPE COMPANY, A CORPORATION OF NEW YORK.

LINOTYPE-MACHINE.

SPECIFICATION forming part of Letters Patent No. 795,028, dated July 18, 1905.

Application filed November 15, 1904. Serial No. 232,838.

To all whom it may concern:

Be it known that I, PHILIP T. DODGE, of Brooklyn, county of Kings, and State of New York, have invented a new and useful Improvement in Linotype-Machines, of which the following is a specification.

My invention has reference more especially to an improvement in the commercial Linotype-machine of the general organization represented in Letters Patent of the United States No. 557,000, wherein a magazine containing a font or set of circulating matrices is arranged in an inclined position in the main frame and adapted to be removed at will in order that it may be replaced by another magazine containing a set or font of matrices with characters of another size or style.

As the machines have been heretofore constructed the magazine, having a heavy base-frame secured thereto to hold it in shape, could be removed only from the rear side and by moving it, together with its base-frame, over a horizontal supporting-bar near its upper end. The elevated position of this bar (about five and a half feet from the floor) and the weight of the magazine were such as to demand an objectionable effort and endanger both the attendant and the magazine. It ordinarily requires the effort of two persons to effect the removal or insertion of the magazine at the rear, and the narrowness of the main frame, the width of the rear end of the magazine, and other features of construction are such as to prevent the removal of the magazine at the front.

The aims of the present invention are to facilitate the removal of the magazine and to reduce the cost of construction. To this end I widen the upper portion of the main frame in such manner as to permit the removal of the magazine from the front instead of the rear, and I provide on the forward part of the frame a roller or equivalent support to aid in sustaining the magazine as it is withdrawn from the front.

I prefer to construct the magazine independently of the usual base-frame and mount a substitute for the latter permanently in place in the main frame, so that it

will serve not only as a support for the magazine when it is in operative position, but also as a guide to assist in sustaining the same during its removal or replacement.

I prefer to mount the escapements for controlling the discharge of the matrices in a supporting-bar distinct from the magazine and secured permanently on the main frame, but the escapements may be carried with the magazine as usual.

I have limited the drawings to those parts of the machine with which my invention is immediately associated. The other parts may be of any ordinary construction and the parts herein shown may be varied in details of form and arrangement at will, provided they have essentially the mode of action herein described.

Figure 1 is a side elevation of the upper part of the machine having my improvement incorporated therein, the magazine with the escapements mounted therein being shown in its operative position. Fig. 2 is a side elevation of the lower front part of the frame with the magazine removed. Fig. 3 is a side elevation similar to Fig. 1 with the magazine in operative position, the magazine in this case being shortened and the escapements mounted in the main frame. Fig. 4 is a side view of the forward end of the parts shown in Fig. 3 with the magazine removed. Fig. 5 is a cross-section on the line 5-5 of Fig. 3, looking in a downward direction.

Referring to the drawings, A represents portions of the main frame, which may be of any construction adapted to receive the operative parts.

B is the inclined magazine, channelled longitudinally and adapted to receive and carry a font or set of matrices, as in the ordinary Mergenthaler machine.

D is a distributor fixed to the main frame and serving to deliver the matrices through an intermediate channelled throat or guide E into the upper end of the magazine.

F is a vertically-channelled front plate into which the matrices, released one at a time from the magazine, are delivered and through which they descend to the usual mechanism

by which they are assembled side by side in a common line.

G represents the escapement devices, arranged one at the lower end of each channel 5 in the magazine for the purpose of releasing the matrices one at a time in the order in which their characters are to appear in print. These escapement devices may be mounted directly in and made permanent parts of the 10 magazine, as shown in Fig. 1, the magazine being suitably lengthened to receive them, as in the commercial Mergenthaler machines of the present day, or, if preferred, the escapements may be mounted in a channeled support H, secured rigidly to the main frame beyond 15 the lower end of the magazine and forming a continuation of the latter, as shown in Fig. 3.

In carrying my present invention into effect I widen the upper end of the main frame A, or, in other words, separate the two upright arms between which the upper end of the magazine is seated in such manner that the magazine, wider at the front than at the 25 rear, may be drawn forward between these arms and removed from the front of the machine, a course heretofore impossible.

I represents a flat skeleton base-frame underlying the magazine, designed to give the 30 same support and to prevent it from sagging or bending out of shape. Heretofore this frame has been secured permanently to the magazine, which was consequently increased in weight and in price thereby. I now make 35 this frame independent of the magazine and bolt it or otherwise secure it rigidly in place in the main frame, seating the magazine B loosely thereon, so that it may be lifted at the front and withdrawn from the machine at 40 will.

Fig. 1 illustrates the manner in which the magazine carrying the escapements is sustained on this frame and removed by lifting it at the front, drawing it forward and canting it downward, as indicated in dotted lines. To facilitate this removal of the magazine, I extend the front end of the main frame upward and mount therein a horizontal transverse roller K or similar support designed to 50 assist in sustaining the magazine as it is moved to and fro thereover. It is obvious that the form of this support may be varied at will, provided only it is adapted to aid in sustaining the magazine and to prevent it 55 from contacting with the channeled front plate F or other parts which could be injured thereby.

The side plates of the magazine (See Fig. 1) are preferably widened vertically, as shown at 60 b, so that in riding on the roller or support K they will sustain the magazine at such height as to prevent the escapements therein, G, from striking the other parts as the magazine is moved to and from its operative position.

When the escapement mechanism is fixed 65 on the main frame, as shown in Fig. 3, these widened side plates are unnecessary, the magazine flat on its under side and sustained on the stationary frame H, as in Fig. 1, being simply lifted at its forward end and passed 70 outward over the roller K, as indicated in dotted lines.

When the magazine without the escapements is employed, means must be provided at the lower end for locking or holding the 75 matrices. I recommend for the purpose a bar thrust through the magazine from side to side between the upper and lower ears of the lowermost matrices, in the manner shown and described in a pending application of Rogers, 80 Serial No. 230,230.

The throat-plate E for dropping the matrices into the magazine from the distributor is preferably hinged at e to the upper end of the fixed base-frame H; but it may be attached to the main frame or hinged to the upper end of the magazine, as in the ordinary commercial linotype.

Having described my invention, what I claim is—

1. In a linotype-machine and in combination with an inclined magazine, removable at will, a main frame provided with means to sustain the magazine in operative position, and constructed substantially as described, 95 to permit the removal of the magazine in the forward direction.

2. In a linotype-machine and in combination with an inclined magazine, removable at will and having its rear end of greater width 100 than its front, a main frame provided with a fixed base-frame underlying and supporting the magazine, said main frame of suitable width to permit the passage of the magazine in a forward direction.

3. In a linotype-machine, an inclined magazine, removable at the front, in combination with a main frame, provided with fixed means for supporting the magazine in operative position, and with means at the front to aid in supporting the magazine during its removal or replacement.

4. In a linotype-machine, a main frame provided with a distributing mechanism for delivering the matrices, a fixed guide-plate to receive the matrices from the magazine, an inclined base-frame fixed in the main frame to sustain the magazine, and a magazine removably seated upon said base-frame in operative relation to the distributor and the guide-plate and removable in an endwise direction at the front of the frame.

5. In a linotype-machine, a main frame, provided with matrix receiving and distributing mechanisms and with a frame to support the magazine, in combination with a magazine laid loosely upon the supporting-frame, that it may be removed at will, and

an elevated roll or support at the front of the machine to sustain the magazine during its removal in a forward direction.

6. In a linotype-machine, an inclined magazine, removable endwise at the front of the machine, in combination with the main frame provided with a support for said magazine, and an escapement mechanism permanently fixed on the main frame in operative relation to the magazine.

7. In a linotype-machine, an inclined magazine removable at the front of the machine, in combination with a main frame provided with a rigid base-frame to support the maga-

zine, matrix-releasing mechanisms mounted 15 rigidly on the main frame in operative relation to the magazine, and a transverse support above the escapements to assist in sustaining the magazine during its removal and replacement.

In testimony whereof I hereunto set my hand, this 7th day of November, 1904, in the presence of two attesting witnesses.

PHILIP T. DODGE.
